NONREFILLABLE BOTTLE

Arthur Laube, Fairhaven, Mass.

Application July 1, 1935, Serial No. 29,392

2 Claims. (Cl. 215—21)

This invention relates to new and useful improvements in non-refillable bottles and containers.

An object of the invention is to provide a non-refillable bottle which is inexpensive to manufacture.

A further object of the invention is to construct a bottle which cannot be refilled with spurious contents once the original contents have been emptied therefrom through the use of a valve which will automatically close when an attempt to refill the bottle is made.

With these and other objects in view, the invention consists in certain new and novel features of construction in combination with parts and arrangements of parts, as will be hereinafter more fully explained.

In the drawing:

Figure 1 is a vertical sectional view through the neck of a bottle, illustrating the invention therein;

Figure 2 is a fragmentary sectional view of the neck of the bottle, showing the bottle in a horizontal position, the valve now being partially open; and

Figure 3 is a fragmentary sectional view of the invention, showing the bottle in inverted position with the valve now completely open.

With reference to the component parts of the invention, it is seen that 1 indicates the neck of a bottle or container which is of a type easily procurable on the market and may be of any type or shape. A sleeve or shell 2 of suitable material is snugly fitted within the neck of the bottle, said sleeve or shell having at its upper terminus an integral flange 5 formed thereon. The sleeve or shell terminates at its lowermost point within the neck of the bottle in a horizontal annular valve seat 3 having an aperture 9 formed therein which is provided for the passage of liquid therethrough. The aperture 9 is beveled at 4 in a suitable manner to facilitate the discharge of the liquid through the said aperture.

A valve 13, either split or solid, is adapted to rest upon seat or wall 3, said valve having a projecting portion 16 at the upper end thereof and a head portion 15 at its lower end. This head portion 15 of the valve is flared out from the projecting portion so as to form a closure of large area for the aperture 9. This head portion may be of any geometrical shape so long as it has a smooth lower face to permit tightly sealing the aperture 9. The valve 13 is of solid construction of any suitable material and has a depression

or hollowed-out portion 14 formed within the projecting portion 16 so that the center of gravity of the mass of valve 13 lies within the head portion 15. This permits a quicker and easier closure of the valve 13 on seat or wall 3, 5 as will be more fully described hereinafter.

Valve 13 is normally adapted to be removable from seat 3, and the sides of valve 13 are not attached to the sleeve or shell and, when in a bottle, it can be seen if valve 13 tumbles or rotates 10 during operation or handling.

A second sleeve or shell 6, having an upper depending flange 7 which rests over flange 5 of sleeve or shell 2, is suitably secured within sleeve or shell 2 so as to be normally not removable therefrom. The sleeve or shell 6 is formed at its lower end with a horizontal annular portion 8 having a central aperture 17 which guides and limits the projecting portion 16 of the valve 13. In the annular portion 8 is formed a web or a series of 20 openings 10 which allow the liquid contents of the bottle to flow therethrough regardless of the position of the valve. Suitably secured to the inner sleeve or shell 6 is a guard member 11 comprising an annular portion 19 and a raised crown 25 portion 18. Apertures 12 are formed about the circumference of the vertical wall of the crown portion 18. The purpose of these apertures is to allow discharge of the contents of the bottle after the same have passed through the valve mechanism.

In the use of a bottle fitted with the novel features of this invention, it will be readily seen that unobstructed discharge of the bottle contents is allowed, but, upon an unauthorized attempt to refill the bottle, the invention operates to prevent it as follows:

If an attempt is made to refill the bottle, the liquid will flow through apertures 12 into depression 14 and through openings 10. Liquid falling into depression 14 will tend to hold valve 13 firmly seated, while liquid that passes through openings 10 will find valve 13 due to its smooth fit on seat 3, effectively sealing the aperture 9. Because of the arrangement of apertures 12 in the vertical wall of crown 18, it is readily seen that no wire or other instrumentality can be inserted through the neck of the bottle to tamper with valve 13, yet free discharge of the liquid is allowed.

This invention may be embodied in various types of bottles now used extensively in the distilling industry, or any other industry dealing in liquids or fluids, and is particularly adaptable to those manufacturers, distributors, or dealers who

desire to guard against spurious refilling of their bottles by unscrupulous parties, which bottles are then resold to the public by such parties in defiance of the law.

5 It is understood that the form of this invention herewith shown and described is to be taken as a preferred example of the same and that various changes in the shape, size, and arrangement of parts may be resorted to without de-
10 parting from the spirit of the invention or the scope of the subjoined claims.

Having thus described the invention, I claim:

1. In a bottle, a sleeve member in the neck thereof having an opening for the passage of liquid therethrough, a valve for sealing said opening, a second sleeve having means for limiting

the opening movement of said valve, and liquid passages through said means, and a guard member formed above said means in the liquid discharge passage protecting said valve.

2. In a guard member for a non-refillable bot- 5 tle, comprising an inner sleeve having at its lower terminus a pair of spaced horizontal annular portions, said lower portion having a central opening forming a valve guide and side open-
10 ings for the passage of liquid therethrough, said upper portion having a central raised portion, laterally formed liquid passages beneath said central portion, and a flanged upper end for limiting the depth of insertion within the bottle. 15

ARTHUR LAUBE.
